UNITED STATES PATENT OFFICE.

GEORGE V. MARTIN, OF CLEVELAND, OHIO, ASSIGNOR TO THE NATIONAL MALLEABLE
CASTINGS COMPANY.

ENGINE-COUPING.

1,170,982.

Specification of Letters Patent.

Patented Feb. 8, 1916.

Application filed June 28, 1913. Serial No. 776,356.

To all whom it may concern:

Be it known that I, GEORGE V. MARTIN, a citizen of the United States, residing at Cleveland, Cuyahoga county, Ohio, have 5 invented new and useful Improvements in Engine-Couplings, of which the following is a specification, reference being had to the accompanying drawings, in which—

Figure 1 is a plan showing the application 10 of my improvements to the pilot beam of a locomotive; Fig. 2 is a front elevation thereof, with the coupler and parts partly broken away; Fig. 3 is a section on lines III—III of Fig. 2; Fig. 4 shows in plan a 15 modified form of my device; Fig. 5 is a section on lines V—V of Fig. 4, and Fig. 6 is a section on lines VI—VI of Fig. 5.

My invention relates to engine couplers, and provides mechanism to permit lateral 20 displacement of engine couplers, which is especially useful in switching operations and on sharp curves.

Referring to the drawings, A indicates the coupler-head, and B the pilot beam of 25 the locomotive. The coupler-head A, which may be of any suitable type, has a short shank 2 with a rounded rear end 3, and laterally projecting wings 4 having pin holes 5 extending vertically therethrough. The 30 coupler-head A is pivotally connected by the pins or bolts 6 to the forked and apertured forward ends of the laterally swinging links 7. The links 7 are pivotally mounted on the pilot beam B by means of the bolts 35 or pins 8. The pin holes 9 in the rear ends of the links 7 are preferably elongated to relieve the links from buffing stresses, and the hubs 10 are lengthened in a vertical direction to provide extended bearing surfaces 40 under draft against the pins 8. Hand holds 11, integral with the links 7, are provided to permit the coupler to be shifted by hand to any desired position, preliminary to making a coupling.

Bolted to the forward face of the pilot beam B is a casting 12 having apertures 13 for the links 7. The apertures 13 are of sufficient width to permit the necessary oscillation of the links 7, and the lower faces 50 of the apertures act as supports for the links 7. The casting 12 is comprised of the buffer segments 14 and 15, curved to the arc of the circle about which the coupler-head swings in its lateral movements, and upper and

lower flanges 16 and 17 respectively extend 55 outwardly beyond the buffer segments 14 and 15. The lower flange 17 acts as a supporting shelf for the rear end of the coupler shank.

Interposed between the faces of the buffer 60 segments 14 and 15 and the rear end 3 of the coupler shank 2 is a double concave wearing shoe 18, the forward face of which is curved to fit the curved rear end 3 of the coupler shank, and the rear face is curved 65 to the same arc as the buffer faces 14 and 15. The pivotal connection of the coupler-head A to the pilot beam B by means of the links 7 permits considerable lateral movement of the coupler-head, and during such 70 lateral movement, the wearing shoe 18 slides laterally upon the buffer segments 14 and 15 and is always interposed between the rear end of the coupler shank and the segments 14 and 15 in position to receive and 75 transmit thereto all of the buffing strains imposed upon the coupler, while the links 7 by reason of their elongated pin holes 9, are relieved of all buffing strains.

The pulling strains are transmitted 80 through the wings 4 to the links 7, and from the links 7 to the pilot beam B. Stops 19 are provided against which the wearing shoe 18 is designed to abut to prevent extreme lateral movement of the coupler-head in either 85 direction.

The elongated holes 9 in the links 7 permit the coupler A to move forwardly to a slight extent in swinging laterally so that the wearing shoe 18 will be relieved from tight 90 contact with the curved buffering segments 14 and 15 on the pilot beam. Friction between these parts is thereby eliminated and the coupler may be moved laterally in either direction without undue effort.

In Figs. 4, 5 and 6 I show a modification 95 of my invention in which the pilot beam B' has a suitable central aperture 20 and buffer segments 14' and 15' integral with the pilot beam B'. The wearing shoe 18' has a rearward extending shank 21 upon which are located buffering springs 22 confined between the followers 23 and 24, and also mounted on the shank 21. The forward follower 23 bears against a collar 25 on the shank 21 and 100 the rear follower 24 has a concave rear face 26 with a socket engagement against coöperating abutments 27 on the bracket 28,

- which is secured to the pilot beam B' , and incloses the spring mechanism just described. The socket engagement of the follower 24 against the abutments 27 permits 5 the wearing shoe 18' with the springs 22 and followers 23 and 24 located thereon to remain always in longitudinal alinement with the coupler-head in position best suited to relieve the buffing shocks regardless of 10 whether or not the coupler remains in the longitudinal center line of the engine.
- The pin holes 9' in the links 7' are sufficiently elongated to permit the rearward movement of the coupler allowed by the 15 buffing springs without throwing buffing strains on the links 7' or on the pins 8'. The links 7' to the rear of the pin holes 9' have upwardly and downwardly extending lugs 29 having concave forward faces which engage correspondingly shaped convex bosses 30, through which the pulling stresses are transmitted to the pilot beam B' . The pins 8' are therefore relieved of both pulling and 20 buffing stresses. The links 7' also have downwardly extending portions 31 which bear on the shelf 32, which forms a support for the links and upon which the links slide in allowing the coupler-head to move laterally.
30. In buffing after the spring resistance has been taken up the wearing shoe 18' comes in contact with the buffer faces 14', and 15', and the remainder of the buffing stress is transmitted therethrough to the pilot beam B' .

As the coupler moves rearwardly under buffing stresses in the initial spring resisted movement, the lugs 29 of the links 7' come out of engagement with the bosses 30, but 40 the lugs 29 are subsequently returned to their socket bearing with the bosses 30 by compression of the springs 21, and are normally always in position to receive pulling strains.

45. Various modifications may be made in the construction which I have shown and described herein without departing from my invention.

What I claim is:

50. 1. A coupler mounted for lateral movement, a buffer segment mounted on the car structure, a shoe interposed between the coupler shank and the segment, and adapted to travel laterally along said segment during 55 lateral movement of the coupler, and links forming the pivotal connection between the coupler and the car structure.
2. In a coupler mounted for lateral movement, a buffer segment on the car structure 60 adapted to permit the coupler to slide bodily in a lateral direction and to take up the buffing stresses from the coupler, and a plurality of links through which the coupler swings radially about a point to the rear of the rear- 65 most portion of its shank, the said links be-

ing adapted to take up the pulling strains and comprising the sole pivotal connection between the coupler and the car structure.

3. In a coupler mounted for lateral movement, a buffing shoe interposed between the 70 coupler and the car structure and adapted for travel laterally with the coupler, and a plurality of links forming the sole pivotal connection between the coupler and the car structure and upon which the coupler swings 75 radially about a point to the rear of the rear-most portion of its shank, the said links being under strain during pulling and being relieved of strain during buffing.

4. A coupler mounted for lateral movement, having a head, and a shank, a buffing segment mounted on the car structure, a shoe 80 adapted to engage said shank and to slide laterally along said segment, and a plurality of links connecting said coupler head with the car structure, said links forming the pivotal mounting of said coupler.

5. In a coupler mounted for lateral movement, a buffer stop on the car structure adapted to restrict rearward movement of 90 the coupler and to take up the buffing strains, and links forming the pivotal connection between the coupler and the car structure, adapted to restrict the forward movement of the coupler and to take up pulling strains, 95 the said stop being inoperative in pulling and the said links in buffing.

6. In an engine coupler mounted for lateral movement, a buffing surface on the pilot beam, a wearing shoe normally out of contact with the buffing surface and having a bearing on its forward face for reception of the coupler shank, pulling links secured at their forward ends to the coupler-head, and at their rear ends to the pilot beam and normally in position to transmit pulling strains. 100

7. In an engine coupler mounted for lateral movement about an axis in the longitudinal center line of the engine, a plurality 110 of links having a pin and socket engagement at their forward ends with the coupler-head, and at their rear ends with the pilot beam, the said links having pulling lugs engaging the pilot beam and adapted to relieve the pin connections with the pilot beam from 115 strain.

8. In an engine coupler mounted for lateral movement, a buffer surface on the pilot beam, a wearing shoe having on its forward side a bearing against the rear end of the 120 coupler shank, and on its rear side a bearing for engagement with the buffer surface, the said wearing shoe having a rearward extension, buffer springs mounted on the said rearward extension, the said buffer springs being adapted to take up the initial buffing shock and to return the coupler-head to normal position, and a plurality of links connecting the coupler-head and the pilot beam for the transmission of pulling strains. 125 130

9. In an engine coupler, a wearing shoe engaging the coupler shank, buffer springs on the wearing shoe, pulling links connecting the coupler-head and the pilot beam, the said wearing shoes, buffer springs, and links and coupler being adapted for radial movement about an axis in the longitudinal center line of the engine.
10. A coupler having a head and a shank, a plurality of links forming a pivotal mounting for said coupler and permitting it to move bodily in a lateral direction, and a buffer segment secured to the pilot beam and in substantial alinement with the coupler shank through its arc of lateral movement, said links being pivoted to the car to the rear of the front face of the pilot beam, whereby an extended bodily lateral movement of the coupler is obtained.
11. A coupler having a head and a shank, a plurality of links forming a pivotal mounting for said coupler and permitting it to swing laterally on the arc of a circle
- whose center is rearward of the rearmost point of the coupler shank, a buffer segment 25 behind said coupler shank and in substantial horizontal alinement therewith, the buffering surface of said segment being curved to substantially the same arc as the arc of swing of said coupler, and a double concave shoe 30 between said segment and said coupler shank.
12. In a coupler mounted for lateral movement, a buffer segment on the car structure for receiving the buffering blows from the 35 coupler, and a plurality of links secured at their forward ends to the coupler head and at their rear ends to the pilot beam, said links being movable laterally and longitudinally by the coupler head, said links being 40 also free to move relatively to the pilot beam during buffering.
